COMBINED CLUB AND FIREARM

Filed Nov. 27, 1928

Inventor
By Reginald F. Sedgley,
Herbert S. Fairbanks
Attorney.

UNITED STATES PATENT OFFICE

REGINALD F. SEDGLEY, OF PHILADELPHIA, PENNSYLVANIA

COMBINED CLUB AND FIREARM

Application filed November 27, 1928. Serial No. 322,204.

The object of this invention is to devise a novel construction and arrangement of a combined club and firearm which can be used as a club and if the user is in danger of being overpowered he can also use the club as a firearm.

A further object of the invention is to devise a novel construction and arrangement of a double acting firing mechanism where-
10 in as the trigger is drawn rearwardly by the operator the firing pin will be automatically released to permit the firing pin spring to effect the operative stroke of such firing pin.

With the above and other objects in view
15 as will hereinafter more clearly appear, my invention comprehends a novel combined club and firearm.

It further comprehends a novel double acting firing mechanism.

20 It further comprehends a novel club having substantially the contour and weight of the ordinary policeman's club and adapted to receive a cartridge, the club having embodied in it a firing mechanism, the trigger
25 of which is normally in an inoperative position. This trigger can be moved into its operative position without the user relinquishing his firm grip on the club by sliding his finger over the trigger, and the trigger is
30 adapted to be actuated by the user without interfering with his grip on the club.

My invention further comprehends a novel construction and arrangement of a club, a novel construction and arrangement of firing mechanism, and novel means for assembling the firing mechanism in the club so that
35 the club has the general appearance of the ordinary policeman's club and is adapted to be taken apart for the insertion of a
40 cartridge into the club or for the removal of a used cartridge therefrom.

It further comprehends a novel double acting firing mechanism wherein the trigger is carried by a cocking sleeve which carries
45 a novel construction of a flexible cocking lever which engages a shoulder on the firing pin and novel means for automatically effecting the release of the cocking lever as the cocking sleeve moves rearwardly.

50 It further comprehends a novel firing

movement in which the firing pin at its forward end bears against a safety spring which tends to move it rearwardly and which is opposed by the firing pin spring.

Other novel features of construction and
55 advantage will hereinafter more clearly appear in the detailed description and the appended claims.

For the purpose of illustrating the invention, I have shown in the accompanying drawings a typical embodiment of it, which, in practice, will give reliable and satisfactory results. It is, however, to be understood that this embodiment is typical only and that the various instrumentalities of
60 which my invention consists can be variously arranged and organized, and that the invention is not limited to the precise arrangement and organization of these instrumentalities as herein set forth.

70 Figure 1 is a top plan view of a combined club and firearm embodying my invention.

Figure 2 is a section on line 2—2 of Figure 1.

Figure 3 is an end view of the forward end
75 of the club.

Figure 4 is a section on line 4—4 of Figure 2.

Figure 5 is a section on line 5—5 of Figure 2.

80 Figure 6 is a top plan view of a portion of the casing of the firing mechanism showing more particularly the cam for automatically effecting the release of the cocking lever.

Similar numerals of reference indicate corresponding parts.

85 Referring to the drawings:—

The club consists of a grasping handle 1 and the body portion 2 which latter is detachable from the grasping portion and which, when assembled, presents the ordinary appearance of a policeman's club. The grasping portion 1 is preferably roughened, turned or indented to enable the user to obtain a firm grasp on the club, and, as illustrated, it is provided throughout the grasping portion with the annular ridges or beads 3.

90 The body portion 2 is provided with a gun barrel 4 which is secured in place by means
95 100

of a nut 5 having spanner receiving openings 6. The barrel 4 at its inner end extends beyond the wooden shell within which it is fixed to form a threaded extension 7 which is in threaded engagement with the internally threaded head 8 of the casing 9 of the firing mechanism which is contained within the wooden shell of the grasping portion 1, which is recessed to receive the casing 9. The casing 9 is provided with a rearwardly extending tubular rod 10 which is externally threaded at one end to receive a cap nut 11 which is received in a recess 12 in the rear end of the club. The cap nut 11 has swivelled to it an apertured pin 13 to which is adapted to be connected the usual leather thong for securing the club to the wrist of the user.

The cap nut 11 abuts against a shoulder 14 and the head 8 abuts against a shoulder 15 so that the casing 9 of the firing mechanism is securely fixed within its outer shell. The tubular rod 10 has slidably mounted in it the firing pin 16 which intermediate its ends is cut away to form a shoulder 17 and a tapered portion 18. The forward end of the firing pin is of reduced diameter to form the firing pin contact member 19 which is adapted to pass through an aperture 20 in the head. At the forward end of the firing pin a safety spring 21 encircles the firing pin proper 19 and is positioned between a shoulder on the firing pin and the juxtaposed wall of the casing 9. This safety spring prevents the firing pin firing the cartridge in case the club is dropped. The rear end of the firing pin has bearing against it one end of a firing pin spring 22 the opposite end of which bears against the cap nut 11.

23 designates the cocking sleeve which is 40 loosely mounted on the tubular extension 10 and this cocking sleeve is maintained in its forward position by means of a retracting spring 24 interposed between the rear end of the cocking sleeve 23 and the cap nut 11.

45 The cocking sleeve is provided with the ears 25 between which is pivoted the trigger 26 by means of a pin 27. The trigger 26 bears against the cocking lever 28 which is in the form of a flat curved spring which is notched 50 out at the sides in order that it will be retained between the ears 25.

The rear end of this cocking lever curves downwardly and inwardly and terminates in a guide portion of reduced width which is 55 adapted to pass into the slot 29 in the tubular rod 10 so that during the rearward travel of the cocking lever with the cocking sleeve, such cocking lever is accurately guided. The tubular extension 10 is provided with the 60 longitudinally extending slot 30 and the top wall of such slot in proximity to the slot 29 forms a cam 31 which causes the cocking lever to move outwardly and affect its release from the shoulder 17 of the firing pin 16. 65 The cocking sleeve is provided with a screw

82 which travels in the slot 29 so that the cocking sleeve has a rectilinear movement.

The trigger 27 is provided with an outwardly curved boss 33. The trigger 26 also has flat faces 34 which bear against the cocking lever 28 so that the latter tends to retain the trigger 26 in both its operative and inoperative positions. The trigger 26 is normally received in the longitudinally extending slot 35 which extends through the outer periphery of the wooden shell of the grasping portion 1 and the boss 33 extends outwardly beyond the surface of the shell so that when the user draws his finger rearwardly over the boss 33 the trigger 26 is in firing position.

The forward end of the grasping portion is provided with a reinforcing ring 36 which is flush with the barrel.

The casing 9 is provided with a centering lug 37 which sets in a recess formed in the wooden shell of the grasping portion. The inner end of the bore 38 is adapted to receive the cartridge which is secured in position by the screwing of the body portion 2 90 into the grasping portion 1.

The operation will now be readily apparent to those skilled in the art and is as follows:—

It will be apparent that the club has the general appearance of the ordinary policeman's club and can be used in the same manner as such club. The barrel 2 is unscrewed and a cartridge of any desired character inserted and the barrel is then screwed to the 100 casing 9.

Assuming now that the user desires to use the club as a firearm this can be accomplished without releasing his grip from the club since by sliding his finger over the boss 33 the trigger 26 will be cocked and by placing the finger in front of the trigger 26 the latter can be drawn rearwardly, thereby drawing with it the cocking sleeve 23.

The cocking lever 28 is at this time in engagement with the shoulder 17 of the firing pin 16 so that the firing pin is moved rearwardly, thereby compressing the firing pin spring 22. During this rearward movement, the cam 31 causes the cocking lever to move outwardly out of engagement with the shoulder 17, thereby releasing the firing pin, so that its spring 22 can impel the firing pin forwardly. The retracting spring 24 is also compressed during this rearward movement of the cocking sleeve, so that, when the trigger is released, the cocking sleeve will move forwardly into its normal or initial position. As the firing pin 16 moves forwardly, the firing pin cartridge contacting portion 19 will pass through the firing pin aperture 20 and cause the firing of the cartridge.

The spring 21 serves as a safety spring by retracting the firing pin to a position where in it is engaged by the cocking lever and is

positively held from forward movement until the trigger is pulled all the way to the rear, whereby disengaging the cocking lever which makes accidental discharge impossible.

5 If the user drops the club the firing pin will not contact with the firing pin to fire it.

It will be apparent that all that the operator has to do to effect the operative movement of the firing mechanism is to draw the 10 trigger 26 rearwardly and the cartridge will be automatically fired.

15 It will be apparent that the firing mechanism can be readily removed whenever desired by unscrewing the cap nut 11 and pushing the casing 9 through the forward portion of the grasping handle 1, the trigger 26 passing beneath the band 36.

20 My present invention discloses a double acting firing movement which is semi-automatic. When the operator draws the trigger rearwardly the cocking sleeve and cocking lever are moved rearwardly until the cocking lever is automatically released from the firing pin but riding up on the cam on the 25 casing. The trigger is normally substantially flush with the outer periphery of the club but when the person who is grasping the club in one hand slides a finger rearwardly over the boss on the trigger, the trigger is 30 cocked and is retained in such position by the resilient cocking lever.

35 The inner end of the gun barrel engages the rim of the cartridge when in assembled position so that the cartridge is retained in firing position. A cartridge may be of any desired or conventional type and the discharge from the cartridge may be of a solid, liquid or gaseous character.

40 The firing pin casing is provided with an abutment which, only for the purpose of illustration, is shown as a cap nut and between such abutment and the firing pin and the cocking member are disposed resilient means such as a firing pin spring and a retracting 45 spring to effect the forward movement of said firing pin and said cocking member.

45 As illustrated the club comprises sections, one section of which is provided with a gun barrel and in the other section firing mechanism is mounted, and the parts are retained in assembled position by the engagement of the gun barrel with the casing of the firing mechanism.

55 It will now be apparent that I have devised a new and useful combined club and firearm which embodies the features of advantage enumerated as desirable in the statement of the invention and the above description, and 60 while I have, in the present instance, shown and described a preferred embodiment thereof of which will give in practice satisfactory and reliable results, it is to be understood, however, that this embodiment is susceptible of 65 modification in various particulars without

departing from the spirit or scope of the invention or sacrificing any of its advantages.

Having thus described my invention what I claim as new and desire to secure by Letters Patent, is:—

70

1. The combination with a policeman's club having a slot, of a firing mechanism concealed within said club and having a trigger disposed in said slot and provided with a boss which effects cocking of the trigger when 75 pressed by the holder of the club.

2. The combination with a policeman's club, of a firing mechanism within said club and having a pivoted trigger which is rocked into cocked position by the holder of the 80 club sliding a finger over the trigger.

3. In a combined club and firearm, a club, and a firing mechanism within it comprising a casing having a cam, a firing pin slidable in said casing and having a shoulder, a cocking member movable along said casing, a cocking lever carried by said member and normally engaging said shoulder, and engaging said cam on its movement in one direction to release said firing pin, a trigger pivoted to said cocking member, a spring for said firing pin, and a retracting spring for said member.

4. In a combined club and firearm, a club, and a firing mechanism within it comprising a casing having a cam, a firing pin slidable in said casing and having a shoulder, a cocking member movable along said casing, a cocking lever carried by said member and normally engaging said shoulder, and engaging said cam on its movement in one direction to release said firing pin, a trigger pivoted to 95 said member and substantially concealed within the planes of said club, a spring for said firing pin, a retracting spring for said member, and a safety spring for said spring pin to prevent the latter operating in case 100 the club is dropped.

5. In a combined club and firearm, a club, and a firing mechanism within it comprising a casing having a cam, a firing pin slidable in said casing and having a shoulder, a cocking member movable along said casing, a resilient cocking lever carried by said member and normally engaging said shoulder, and 115 engaging said cam on its movement in one direction to release said firing pin and reengaging with said shoulder on its movement in an opposite direction, a trigger pivoted to said member, a spring for said firing pin, and a 120 retracting spring for said member.

6. In a combined club and firearm, a sectional club, a firing movement in one section, and a gun barrel in the other section detachably connected with said firing movement, 125 said movement including a casing having a shoulder at one end, and a nut at the opposite end of the casing to retain it in its section.

7. In a combined club and firearm, a sectional club, a firing movement in one section, 130

and a gun barrel in the other section detachably connected with said firing movement, said movement including a casing having a shoulder at one end, a nut at the opposite end of the casing to retain it in its section, and a thong receiving means connected with said nut.

8. A double acting firing movement, comprising a casing provided with a cam and having an abutment at one end, a firing pin in said casing and provided with a shoulder, a cocking member slideable along said casing, a cocking lever carried by said member, normally engaging said shoulder, and released by said cam from said shoulder on its rearward movement, a pivoted trigger to move rearwardly said member, a spring between said abutment and firing pin to effect its forward movement, and a spring between said abutment and member to move forwardly said member.

9. A double acting firing movement, comprising a casing provided with a cam and having an abutment at one end, a firing pin in said casing and provided with a shoulder, a cocking member slideable along said casing, a cocking lever carried by said member, normally engaging said shoulder, and released by said cam from said shoulder on its rearward movement, a trigger pivoted to said cocking member and adapted to move rearwardly said member, a spring between said abutment and firing pin to effect its forward movement, a spring between said abutment and member to move forwardly said member, and a safety spring for said firing pin to prevent accidental operation of said firing pin.

10. A double acting firing movement, comprising a casing having an opening in one side, and a cam, a firing pin in said casing having a shoulder, a cocking member slideable along said casing, a cocking lever carried by said member, extending into said opening to engage said firing pin shoulder and actuated by said cam when moved in one direction to disengage it from said shoulder, a trigger pivoted to said cocking member and adapted to move said member in one direction, and resilient means to move said member and firing pin in a direction opposite to that in which they are moved by said trigger.

11. A double acting firing movement, comprising a casing having a chamber and a cam, and a firing pin opening at one end, a firing pin mounted in said chamber provided with a shoulder and having a reduced end to pass through said opening, a safety spring tending to prevent said reduced end passing through said opening, a cocking sleeve slideable on said casing, a cocking lever carried by said sleeve normally engaging said shoulder and released from said shoulder by said cam, a trigger pivoted to said sleeve, a re-

tracting spring for said sleeve, and a spring to effect the firing movement of said firing pin.

12. A double acting firing movement, comprising a casing, a firing pin therein, a cocking member, a trigger pivoted to said member, a cocking lever normally engaging said firing pin, means to release said member from said pin to permit its firing movement and means to effect the firing movement of said firing pin when it is released.

13. A double acting firing movement, comprising a casing, a firing pin in said casing, a cocking member slideable along said casing, a trigger pivoted to and bodily movable with said member, a cocking lever engaging said firing pin to move it in one direction and automatically disengaged from it during such movement, and means to move said firing pin in the opposite direction when disengaged.

14. A firing movement comprising a spring pressed firing pin, a cocking lever engaging with said pin to retract it, a safety spring to retract said firing pin into engagement with said pin to prevent its forward movement until released from said cocking lever, a pivoted trigger to effect movement of said cocking lever, and means to release said cocking lever from said firing pin when the latter is retracted.

REGINALD F. SEDGLEY.
